PRESSER FOOT FOR SEWING MACHINES

Charles F. Rubel, Chicago, Ill., assignor to Union Special Machine Company, Chicago, Ill., a corporation of Illinois

Application April 15, 1931. Serial No. 530,350

9 Claims. (Cl. 112—235)

The invention relates to new and useful improvements in presser foot for sewing machines, and more particularly to a presser foot for use on a machine for trimming the upturned edge portions of fabric sections, turning said trimmed edge portions into flat lapped relation and joining the same by covering stitches.

An object of the invention is to provide a presser foot for a machine of the above character having non-flexible members located alongside the channel which receives the upturned edge portions of the fabric sections, with means whereby said non-flexible members can be readily and quickly detached from the presser foot and replaced thereon without requiring the disassembling of the parts of the presser foot.

A further object of the invention is to provide a presser foot of the above character wherein the non-flexible members terminate substantially at the rear side of the needle opening in said presser foot with a non-flexible member located in rear of the needle opening, and wherein in said non-flexible members constitute substantially the entire fabric holding surface of the presser foot.

These and other objects will in part be obvious and will in part be hereinafter more fully disclosed.

In the drawings—

Figure 1 is a side view of a portion of a sewing machine having the improved presser foot applied thereto;

Fig. 2 is a plan view of the same;

Fig. 3 is a view partly in section and partly in plan showing the shank and foot portion with the parts carried thereby;

Fig. 4 is a bottom plan view of the parts shown in Fig. 3;

Fig. 5 is a sectional view through the presser foot, showing the manner of supporting one of the non-flexible members alongside of the channel, and also the non-flexible member in rear of the needle opening;

Fig. 6 is a view similar to Fig. 5, but showing the non-flexible member partly detached from the foot portion;

Fig. 7 is a perspective view of the non-flexible member at the right of the presser foot as viewed in the direction of feed;

Fig. 8 is a perspective view of the non-flexible member at the left of the presser foot;

Fig. 9 is a view similar to Fig. 5, but showing a fabric section with a cross seam as it enters beneath the foot;

Fig. 10 is a similar view, but showing the cross

seam as having passed the needles and about to pass beneath the non-flexible member at the rear of the foot;

Fig. 11 is a view similar to Fig. 9, but showing the cross seam beneath the non-flexible member at the rear of the foot;

Fig. 12 is a view in transverse section through the presser foot, and throat plate on a line in front of the trimming mechanism and showing more or less diagrammatically the position of the fabric sections before the edge portions are trimmed.

Fig. 13 is a view similar to Fig. 12 taken at the trimming point and showing the edge portions as trimmed off.

Fig. 14 is a view similar to Fig. 12 taken a short distance in front of the needles, and showing the turning down of the trimmed edge portions.

Fig. 15 is a view similar to Fig. 12 taken at the stitching point and showing the fabric sections turned down for stitching.

Fig. 16 is a view similar to Fig. 15, but showing two thicknesses of fabric at the right of the line of feed, and

Fig. 17 is a view similar to Fig. 15, but showing two thicknesses of fabric at the left of the line of feed.

The invention is directed to a presser foot for sewing machines which is especially adapted for guiding and directing fabric sections so that they may be trimmed, after which the trimmed edges are placed in lapped relation and united by stitching, which not only joins the edge portions but which covers the raw edges of the trimmed fabric sections. The presser foot is provided with a channel extending in the general direction of the feed from the front end of the foot to a point directly in front of the needle opening. This channel receives the upturned edge portions and directs the same to horizontally disposed trimming devices which trim said edge portions, after which the presser foot operates thereon for turning said trimmed edge portions into lapped relation for stitching. The stitching mechanism preferably includes a plurality of needles, as shown in the drawings, with which loopers cooperate, and also cover thread laying devices.

The invention is directed broadly to the construction of that portion of the presser foot which bears on the fabric sections and holds said sections either on the work support or in contact with the feed dogs during the operation of the machine. Located along each side of the channel for directing the upturned edge portions is a non-flexible member. Each non-flexible mem-

ber is provided with two posts one at each end thereof. The rear post extends through an opening in the foot portion, and a flat spring bears on the upper end thereof. The front post extends through a slot in the foot portion which leads all the way to the front end thereof, and there is a pin through the post which serves as a stop for limiting the downward movement of the non-flexible member. A spring bears on the forward upturned end portion of the non-flexible member and yieldingly forces said forward end downwardly away from the foot portion. This non-flexible member terminates substantially at the rear end of the needle opening in the foot portion, and there is a third non-flexible member extending all the way across the presser foot in rear of the needle opening. This non-flexible member is yieldingly pressed downwardly and is so constructed that it can move both above and below the plane of the lower face of the non-flexible members when said members are in contact with the foot portion.

It is thought that the invention will be better understood by a detail description of the illustrated embodiment. The presser foot includes a shank portion 1 in the form of a block which is attached to a presser bar 2. Rigidly carried by the shank portion 1 is a foot portion 3. There is a needle opening 4 through this foot portion through which the needles indicated at 5, 6 and 7 pass. There is a channel 8 in the foot portion leading from the front end thereof and terminating in advance of the needle opening. As shown in the drawings, the machine is provided with a work supporting arm 9, and said work arm carries a rib 10 which is V-shaped in cross section, which rib is removably mounted on the work arm so that it can be moved into the channel in the presser foot. The purpose of the rib is to aid in the guiding and directing of the upturned edge portions of the fabric sections. The presser foot is provided with a section 11 secured thereto by a screw 12 which carries a fabric engaging member 13 that operates on the edge portions of the fabric sections to turn the same downwardly into lapped relation. There is also a fabric engaging section 14 secured to the foot portion by a screw 15 which carries a member 16 (see Fig. 14) that turns down the under fabric section prior to the turning down of the upper fabric section by the member 13. Thus it is that the fabric sections are placed in lapped relation one on the other preparatory to stitching.

The fabric sections as they pass into the channel are directed first to trimming devices which include a stationary trimming blade 17 and a movable trimming blade 18. The stationary trimming blade 17 is secured to the foot portion by means of a clamping member 19. Said clamping member is secured to the foot portion by means of a clamping screw 20. This clamping member overlaps the stationary trimming blade and firmly secures the same to the foot portion. The movable trimming blade is provided with a guiding finger 21 and the clamping member is formed with a passageway 22 which receives this guiding finger, and thus it is that the stationary trimming blade is firmly clamped to the foot portion, and at the same time, ample space is given for the movements of the movable trimming blade and the guide finger associated therewith. Fixed to the presser foot is a guard plate 23 which deflects away from the stitching mechanism the trimmed off edge portions. This guard plate is

attached to the foot portion by means of a screw 24.

After the fabric sections have been trimmed they are turned down into flat relation as stated above. The center needle 6 is located so as to pass through the lapped portions while the needles 5 and 7 pass outside of the respective edges, and thus it is that the lapped edge portions are covered by the stitch forming mechanism. The stitch forming mechanism includes a guide 25 for the cover thread and a hook 26 which cooperates therewith in laying the cover thread so that it will join the outside rows of needle thread loops. In the work arm is a complementary stitch forming mechanism which cooperates with the needles for forming connected rows of loops which cover the under face of the lapped sections.

At each side of the channel 8 in the presser foot is a non-flexible fabric engaging portion. The non-flexible member at one side is indicated at 27 and the non-flexible member at the other side is indicated at 28. This non-flexible member 27 has its outer edge at the outer face of the presser foot portion 3. Its inner edge extends along the channel through which the upturned edge portions are guided. There is a portion cut away for the member 13 which aids in the turning down of the edge portions of the fabric sections. The non-flexible member 28 has its outer edge substantially in line with the outer edge of the foot portion 3, while the inner edge is parallel with the wall of the channel in the foot portion. The inner edge at the rear end of the channel is cut away to provide a space for the member 16 which aids in turning down the edge portions of the fabric sections.

In Fig. 5 of the drawings, the mounting of the non-flexible member 28 is shown. Adjacent the rear end of the non-flexible member is a post 29 which extends up through an opening in the presser foot portion 3. Attached to the presser foot is a flat spring 30 by means of a screw 31. This flat spring overlies the upper end of the post 29. The post 29 is of sufficient length so that when the non-flexible member 28 is in contact with the under face of the presser foot portion 3, the spring will be under tension, and yieldingly pressing down on the post 29. The front end of the non-flexible member 28 is turned upward as indicated at 32. Adjacent the front end of the non-flexible member 28 is a post 33 which extends up through a slot 34 leading in from the front end of the presser foot portion 3. A pin 35 extends through the head of this post and is so positioned that when the non-flexible member 28 is against the under face of the foot portion 3, the pin will be a slight distance above the upper face of the foot portion. A spring 36 is secured to a projecting lug carried by the foot portion 3 by means of a screw 37. This spring extends over the front end of the non-flexible member 28 and bears on said non-flexible member. When the presser foot is raised from the fabric, the flat spring 30 bearing on the rear post, and the spring 36 bearing on the forward end of said non-flexible member 28 will yieldingly force said member downwardly away from the foot portion 3. The extent to which the front post moves downwardly is limited by the stop pin. There is nothing to limit the downward movement of the post 29, except that the forward post 33 serves as a fulcrum and the spring 36 bearing on the front end of the non-flexible member 28 will tend to hold the post 29 against the under face of the leaf spring 30. When it is desired to remove this non-flexible

member of the presser foot, all that is necessary is to lift the presser foot and then the rear post 29 can be withdrawn from the opening as shown in Fig. 6, after which the non-flexible member 5 is moved forward, withdrawing the post 33 from the slot 34. The spring 36 is so positioned that the post 33 can be completely withdrawn from the slot. This removing of the non-flexible member is of great aid in the operation of the machine.

10 The lint from the trimming mechanism has a tendency to collect between the non-flexible member and the presser foot and thus limit its action, if not rendering it completely ineffective. The non-flexible member can be very readily and 15 quickly removed without disassembling any of the parts of the presser foot, or by removing any screws or bolts, and when replaced it will be in its normal position under its normal tension means.

20 The non-flexible member 27 carries a post 37 adjacent its rear end, and a leaf spring 38 secured to the foot section by a screw 39 bears on the upper end of the post. There is a post 40 adjacent the front end of this non-flexible member 27, 25 and a pin 41 which limits the downward movement thereof. There is a spring 42 carried by a lug 43 which bears on the forward end of this non-flexible member 27. The proportioning of the parts supporting this non-flexible member 27 and 30 the operation of the same, is precisely the same as the supporting and operation of the non-flexible member 28. The non-flexible members 27 and 28 and the yielding mounting of the same per se, form no part of the present invention, but 35 are shown, described and claimed in the patent granted Alfred T. Chidley, August 25, 1931, No. 1,820,438.

The present invention has particularly to do with the mounting of these non-flexible members so that they may be detached from the foot portion of the presser foot, and also so that they form substantially the entire fabric holding surface of the presser foot in front of the needle. The devices carried by the presser foot for turning 45 the edge portions of the fabric sections into lapped relation and the retractable rib on the work support form no part of the present invention per se, but are shown, described and claimed in the patent granted Albert S. Riviere and 50 Charles F. Rubel, October 13, 1931, No. 1,827,613.

The non-flexible members 27 and 28 terminate substantially at the rear side of the needle hole 4 in the presser foot. In rear of these non-flexible members 27 and 28 and extending all the way 55 across the presser foot is a non-flexible member 44. The foot portion 3 is provided with a recess in its under face adapted to receive this non-flexible member 44. The member is carried by a post 45 extending upwardly into a recess 46 in 60 the shank 1 of the presser foot. A spring 47 housed in the recess yieldingly moves the post downwardly, and the non-flexible member 44 away from the foot portion 3. A screw 48 passing through a slot in the presser foot shank is 65 threaded into the post and limits its downward movement.

The non-flexible members 27, 28 and 44 constitute substantially the entire fabric engaging and holding surface of the presser foot. The 70 underneath portions of the foot adjacent the non-flexible members may be of any desired shape, as they do not engage the fabric and never serve as a fabric engaging and holding surface.

75 The purpose of these non-flexible members

will be understood by reference to Figures 9 to 17, inclusive. In Fig. 9, a fabric section F having a cross seam c is shown as passing beneath the presser foot. This cross seam will raise the forward end of the presser foot slightly. The rear end of the non-flexible member in front of the needle hole will be forced by the leaf spring bearing on the rear post downwardly into contact with the fabric section. The non-flexible member 44 in rear of the needle hole will, of course, bear upon the fabric, notwithstanding that the presser foot has been raised by the cross seam passing beneath the same. In Fig. 10, the cross seam is shown as having passed all the way to the rear end of the non-flexible members in front of the needle hole. It will be seen from this figure that the spring at the forward end of the foot has forced the non-flexible member downwardly into contact with the material following the cross seam. In Fig. 11 the cross seam has passed the needles and is underneath the non-flexible member 44. The presser foot is still held raised, but the non-inflexible members in advance of the needle hole are moved down on to the fabric and thus hold the fabric against the work support and the feed. It will be seen that the cross seams, whether they are in one or both sections of the fabric, will readily pass beneath the presser foot without disturbing the complete control of the fabric sections, both in front and in rear of the cross seam. In Fig. 12 the presser foot is shown as bearing on two fabric sections, one at each side of the line of feed; the edge portions are raised and are being directed to the trimming devices. In Fig. 13 the 110 trimming devices have operated to trim the upstanding edge portions preparatory to the turning of the same down into flat relation for stitching. In Fig. 14 the presser foot is operating upon these trimmed upturned edge portions so as 115 to fold down the one at the left first, and then the one at the right on top thereof. In Fig. 15 the fabric sections are shown in lapped relation and being stitched by the three needles, the center one of which penetrates the lapped sections, while the other two pass outside of the edges of the respective fabric sections. In Fig. 16 there are shown two fabric sections at the right of the line of feed. This causes the presser foot portion 3 to be raised. The non-flexible 120 member 27 is directly against the under face of the foot portion 3. The non-flexible member 28 has, however, through the action of the springs thereon, moved downwardly into contact with the single layer of fabric and is holding the same 130 against the work support and the feet. In Fig. 17 there are two sections of fabric on the left, and the non-flexible member 27 is moved down into contact with the single thickness of fabric.

It will be apparent from the above that a 135 presser foot has been provided wherein the fabric engaging portions at each side of the channel directing the upturned edge portions are non-flexible. They are substantially rigid metal parts, and at the same time, said sections are so mounted that they may yield independently of each other, and yield either at the forward end or the rear end thereof, so as to take care not only of different thicknesses of fabric on opposite sides of the channel, but also cross seams as they pass 145 beneath the presser foot. In order that these non-flexible members will freely move so as to control the fabric sections under all of these conditions, it is essential that the presser foot should be kept clear of collecting lint formed 150

during the trimming of the fabric sections. Either of the non-flexible members 27 or 28 may be very quickly removed from the presser foot for the purpose of clearing away any accumulating lint, and just as quickly restored without dis- 5 assembling any of the parts, or without requiring the use of any implements.

It is obvious that minor changes in the details of construction and the arrangement of the 10 parts may be made without departing from the spirit of the invention as set forth in the appended claims.

Having thus described the invention, what I 15 claim as new and desire to secure by Letters-Patent, is—

1. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member beneath the foot portion at each side of the channel, means for supporting each non-flexible member whereby it may be detached from the foot portion by a tilting and endwise movement of the non-flexible member relative to said foot portion, and yielding means associated with each non-flexible member for moving the same downwardly and away from the foot portion.

2. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member at each side of said channel extending from the front end of the presser foot to a point in line with the rear side of the needle opening, a non- 45 flexible yielding member in rear of the needle opening, said non-flexible members serving as the sole fabric holding surface of said presser foot, and means associated with each non-flexible member for supporting the same and for yieldingly forcing said member downwardly away from the presser foot.

3. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member at each side of said channel extending from the front end of the presser foot to a point in line with the rear side of the needle opening, a non-flexible yielding member in rear of the 65 needle opening, said non-flexible members serving as the sole fabric holding surface of said presser foot, and means associated with each non-flexible member for supporting the same and for yieldingly forcing said member downwardly away from the presser foot, said member in rear of the needle opening being mounted so as to move both above and below the plane of the lower faces of the non-flexible members along side of the channel.

4. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member beneath the foot portion at each side of the channel, means associated with each non-flexible member for supporting the same on said foot portion, said supporting means including devices located substantially at the opposite ends of the non-flexible members, and yielding means associated therewith for normally forcing the non-flexible members downwardly away from the foot section, said supporting means for said non-flexible members being constructed so as to permit the non-flexible members to be independently detached from the foot portion by a tilting and endwise movement of said non-flexible members relative to the foot portion.

5. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member beneath the foot portion at each side of the channel, and means associated with each non-flexible member for supporting the same on the foot portion including a post rigid with the non- 100 flexible member adjacent each end thereof, said posts extending through openings in the foot portion, said opening at the front end of the foot portion being in the form of a slot extending to the front end of the foot so as to permit the non- 105 flexible member to be quickly removed from the foot portion, and means for yieldingly moving said non-flexible member downwardly away from the foot portion.

6. A presser foot for sewing machines comprising a shank, a foot portion rigidly carried by said shank having a needle opening and a channel leading from the front end of said foot portion to a point in front of the needle opening for receiving and directing the upturned edge 110 portions of fabric sections, said presser foot having means for turning said fabric sections into flat overlapping relation for stitching, a non-flexible member beneath the foot portion at each side of the channel, and means associated with each non- 115 flexible member for supporting the same on the foot portion including a post rigid with the non- flexible member adjacent each end thereof, said posts extending through openings in the foot portion, said opening at the front end of the foot portion being in the form of a slot extending to the front end of the foot so as to permit the non- 120 flexible member to be quickly removed from the foot portion, and means for yieldingly moving said non-flexible member downwardly away from the foot portion.

7. A presser foot for sewing machines comprising a shank, a foot portion rigidly carried by said shank having a needle opening and a channel leading from the front end of said foot portion to a point in front of the needle opening for receiving and directing the upturned edge 125 portions of fabric sections, said presser foot having means for turning said fabric sections into flat overlapping relation for stitching, a non-flexible member beneath the foot portion at each side of the channel, means associated with each non- 130 flexible member for supporting the same on the foot portion including a post rigid with the non- flexible member adjacent each end thereof, said posts extending through openings in the foot portion, said opening at the front end of the foot portion being in the form of a slot extending to the front end of the foot so as to permit the non- 135 flexible member to be quickly removed from the foot portion, a flat spring engaging the post at the rear end of each non-flexible member for yieldingly moving the non-flexible member downwardly and away from the foot portion, means carried by the post adjacent the front end of each non-flexible member for limiting the downward movement thereof, and a spring bearing on 140 each non-flexible member in front of the posts for yieldingly moving the front end of the non- 145 flexible member downwardly and away from the foot portion.

8. A presser foot for sewing machines comprising a shank, a foot portion rigidly carried by said shank having a needle opening and a channel leading from the front end of said foot portion to a point in front of the needle opening for receiving and directing the upturned edge portions of fabric sections, said presser foot having means for turning said fabric sections into flat overlapping relation for stitching, a non-flexible member beneath the foot portion at each side of the channel, means associated with each non- 150 flexible member for supporting the same on the foot portion including a post rigid with the non- flexible member adjacent each end thereof, said posts extending through openings in the foot portion, said opening at the front end of the foot portion being in the form of a slot extending to the front end of the foot so as to permit the non- flexible member to be quickly removed from the foot portion.

- prising a shank, a foot portion rigidly carried by said shank having a needle opening and a channel leading from the front end of said foot portion to a point in front of the needle opening for 5 receiving and directing the upturned edge portions of fabric sections, said presser foot having means for turning said fabric sections into flat overlapping relation for stitching, a non-flexible member beneath the foot portion at each 10 side of the channel, means for supporting each non-flexible member whereby it may be quickly detached from the foot portion, yielding means associated with each non-flexible member for moving the same downwardly and away from 15 the foot portion, said non-flexible members terminating substantially at the rear end of the needle opening, a non-flexible member located in rear of the needle opening and extending all the way across the presser foot, a supporting post 20 therefor, said shank having a recess adapted to receive said post, a spring in said recess normally forcing the post downwardly, and a stop for limiting said downward movement of the post, said stop being disposed so as to permit the non- 25 flexible member in rear of the needle opening to move above and below the plane of the lower face of the non-flexible members when in contact with the foot portion.
8. A presser foot for sewing machines including 30 a foot portion, a non-flexible member located beneath said foot portion, a post adjacent each end of said non-flexible member, said foot portion having openings therethrough for receiving said
- posts, a leaf spring bearing on the post at the rear end of said non-flexible member, a limiting pin passing through the post at the forward end of said non-flexible member, said non-flexible member having an upturned forward portion in front of said posts, and a spring bearing on said front end of the non-flexible member for normally forcing said non-flexible member downwardly away from the foot portion and for holding the rear post in contact with the spring associated therewith. 35
9. A presser foot for sewing machines including a foot portion, a non-flexible member located beneath said foot portion, a post adjacent each end of said non-flexible member, said foot portion having openings therethrough for receiving said posts, a leaf spring bearing on the post at the rear end of said non-flexible member, a limiting pin passing through the post at the forward end of said non-flexible member, said non-flexible member having an upturned forward portion in front of said posts, and a spring bearing on said front end of the non-flexible member for normally forcing said non-flexible member downwardly away from the foot portion and for holding the rear post in contact with the spring associated therewith, the opening for the post at the front end of the non-flexible member being slotted whereby said non-flexible member, when the presser foot is raised, can be quickly released from the foot by withdrawing the rear post from the opening and moving the front post forward in the slot. 40
